SILK SCREEN CLAMPING ARRANGEMENT

BACKGROUND OF THE INVENTION

1. Field of the Invention

This invention relates generally to clamping apparatus particularly adapted for use in silk screen printing.

2. Description of the Prior Art

In the making of posters, signs and the like by silk screen printing, it is the usual practice to first make a photograph or a drawing. The drawing or photograph is then hand cut to make a stencil which is then adhered to silk mounted on a frame; photographic stencils also are used. The silk screen is then used repeatedly to place the representation on paper, cardboard or the like. This work is usually done on a table of some sort. Register guides mounted on the table make possible lining up the silk screen with the paper, cardboard, or, alternatively, the original art work can be placed under the screen for registry purposes. It is desirable that the silk screen with its frame be movable away from the table upon which such work is done but it is also desirable that the silk screen with its frame be repositionable in exactly the same position from which it moved.

SUMMARY OF THE INVENTION

One embodiment of the present invention might include clamping apparatus for use in silk screen printing comprising a first angle element, a first clamping jaw, a first stud secured to said first angle element and extending through said first clamp, a wingnut received on said stud and urging said first clamping jaw into clamping relation with said first angle element, a second angle element, a second clamping jaw, a second stud secured to said second angle element, said second clamping jaw being receivable on said second stud for clamping cooperation with said second angle element, a wingnut receivable on said second stud for urging said second clamping jaw into clamping relation with said second angle element, said first clamping jaw and said second angle element being hingedly connected to one another.

One object of this invention is to provide a clamping apparatus which facilitates silk screen printing.

Another object of this invention is to provide clamping apparatus which makes possible accurate and rapid positioning and repositioning of a silk screen with its frame on a table.

Related objects and advantages will appear as the description proceeds.

BRIEF DESCRIPTION OF THE DRAWINGS

FIG. 1 is a perspective view of a table having the silk screen clamping arrangement of the present invention in use thereon.

FIG. 2 is a view of another table showing the clamping arrangement of the present invention in a different operating position on the table of FIG. 2.

FIGS. 3 and 4 are enlarged perspective views of a portion of the structure illustrated in FIG. 1 and showing the structure in two different operating positions.

FIG. 5 is an enlarged perspective view of a portion of the structure illustrated in FIG. 1.

DESCRIPTION OF THE PREFERRED EMBODIMENT

Referring now more particularly to FIG. 1, there is illustrated a table 10 on which is mounted a hinge bar 11. The hinge bar 11 is fixed in position at its opposite ends by clamping apparatus 12 which is shown in greater detail in FIG. 5. Also shown in FIG. 1 are further clamping apparatus assemblies 15, 16, 17 and 18. FIGS. 3 and 4 show representative examples of the clamping assemblies 15, 16, 17 and 18. In FIG. 1, there is also illustrated a relatively large silk screen 20 with its frame 21 as well as a smaller silk screen 22 with its frame 23.

Referring to FIG. 2, there is illustrated a clamping assembly 25 which includes a second angle element 26 and a second

clamping jaw 27. The second angle element 26 has generally an angle shape configuration which includes the two legs 30 and 31. The leg 31 is thickened at 32 to provide a cylindrical bore (not shown) through which the pin 35 passes and also to provide a location for a tapped bore for the fixed mounting of a stud 36. The stud 36 extend through a suitable bore in the clamping jaw 27. Threadedly received upon the stud 36 is a wingnut 40 which is used to urge the clamping jaw 27 into clamping relation with the angle element 26.

10 The pin 35 extends through a bifurcated yoke portion 41 of a first angle element 42. The element 42 also has basically an angle shape including the one leg 45 and a further leg 46 which is substantially thicker than the leg 45 and which also is integral with the bifurcated yoke portion 41. The leg 46 is provided with a pair of countersunk bores 47 which may be used, if desired, to fix the element 42 to the table 50.

The thickened leg 46 of the element 42 also provides a location for a tapped bore to receive a stud 51 upon which is received a first clamping jaw 52 which may be urged into clamping relation toward the angle element 42 by means of a wingnut 60 threadedly received upon the stud 51. As shown in FIG. 2 the elements 26 and 42 each functions as a clamping jaw; however, as will become evident from the other figures of the application the element 26 in some cases does not so function and the same can be true for the element 42. It will be noted that the structure as arranged in FIG. 2 permits the silk screen 61 with its frame 62 to be swung upwardly about the axis of the pin 35 away from the table 50 so as to permit the

20 placing of various work and the like underneath the silk screen 61. It can also be appreciated that when the silk screen 61 with its frame 62 is swung back into the illustrated position it will always be repositioned accurately and precisely at the same position in which it was previously located. It should be noted

25 that the thickness of the legs 45 and 30 of the members 42 and 26 is not substantial so that the frame 62 upon which the silk screen 61 is mounted is not spaced a substantial amount away from the table 50. Thus, in one embodiment of the invention the total thickness of these two legs is less than a quarter of an inch.

Referring now to FIG. 3, it can be seen that the element 26 does not function as a clamping jaw but instead functions only as a mounting member for the stud 36. As shown in FIG. 1, the stud 36 may be replaced with a much longer stud 70' so as to make possible use of the clamping apparatus of the present invention for clamping in position a silk screen 22 which is spaced a substantial distance away from the hinge bar 11. In FIG. 3, the hinge bar 11 is shown as having mounted thereon the first angle element 42 and the first angle element 52 which are fixed together by the stud 51 and the wingnut 60. The second angle element 26 is shown as hinged to the first angle element 42 by means of the pin 35. The stud 36 is shown with a jambnut 70 which may be used if desired and necessary.

55 The stud 36 has fixed thereto another clamping jaw element 75 which is identical to the second angle element 26. The stud 36 is threaded into a suitable tapped bore identical to the tapped bore in the second angle element 26. Received on the stud 36 is the wingnut 40 as well as the clamping jaw 27. The wingnut 40 is tightened down against the clamping jaw 27 causing it to move into clamping relation with the clamping jaw 75 and clamping the frame 21 of the silk screen 20 in position. It can be appreciated that the structure illustrated in FIG. 3 permits the frame 21 to be swung upwardly away from the illustrated position of FIG. 1 on the table up to a position which permits removing and replacing of materials beneath the screen 20. Such swinging or hinging is about the axis of the pin 35.

60 Referring to FIG. 4, there is illustrated an assembly which is 65 in many respects identical to the assembly of FIG. 3. Thus, the hinge bar 11 is provided as are the various parts 70, 36, 26, 42, 60, 52 and 35 identical to the above-described structure of FIG. 3. In FIG. 4, however, certain additional structure is shown as including a turnbuckle 80 which is threadedly connected to the stud 36. Threadedly received within the turn-

70 buckle 80 is a pin 35 which is received through a bore in the angle element 42 and through a bore in the clamping jaw 27. The turnbuckle 80 is provided with a wingnut 60 which is received on the stud 36 and which urges the clamping jaw 27 into clamping relation with the angle element 42. The turnbuckle 80 is provided with a pair of countersunk bores 47 which may be used, if desired, to fix the element 42 to the table 50.

buckle 80 is a further stud 81. Optionally received upon the further stud 81 may be a jam nut 82.

In FIG. 4 the clamping jaws 27 and 75 are shown in somewhat reversed position. In other words, the stud 81 is threaded into the thickened portion 82 of the clamping jaw 27. The bore through the clamping jaw 27 is used to receive stud 85 which is threaded into a suitable tapped bore in the clamping jaw 75. The wingnut 40 is received on stud 85 and forces the clamping jaw 27 against clamping jaw 75. A jamnut 86 may be optionally received upon the stud 81, and functions to fix the stud 81 relative to the clamping jaw 27. The structure of FIG. 4 as well as the structure of FIG. 3 permits swinging the frame 21 of the silk screen away from the table 10 for removing and replacing work and the like beneath the silk screen 20. The turnbuckle 80 also permits accurate fine adjustment of the position of the frame 21 to precisely locate the art work on the silk screen in proper registry. When the apparatus is used as shown for the silk screen 22 in FIG. 1, the stud 36 is replaced by the much longer stud 70'. When the apparatus is so used, a paper or cardboard of relatively large size can be printed at more than one location on the paper by inverting the paper for the various printings.

Referring now to FIG. 5, the manner of using the present invention to secure the hinge bar 11 in place is illustrated. As shown in FIG. 5, the clamping jaw 75 is used along with the clamping jaw 27, the stud 85 and the wingnut 40 to clamp the hinge bar in place to the table 10.

It should also be mentioned that an easy convenient means for keeping the pin 35 in position is a piece of an adhesive tape which is applied over the head of the pin and contacts the member 42. The loose hinge pin 35 is not threaded and, except for its enlarged head, is cylindrical in configuration.

It will be evident from the above description that the present invention provides an improved clamping apparatus which facilitates silk screen printing. It will also be evident that the clamping apparatus of the present invention makes possible accurate and rapid positioning and repositioning of a silk screen and frame on a table.

I claim:

1. Clamping apparatus for use in silk screen printing comprising a first angle element, a first clamping jaw, a first stud secured to said first angle element and extending through said first clamping jaw, a wingnut received on said stud and urging said first clamping jaw into clamping relation with said first angle element, a second angle element, a second clamping jaw, a second stud secured to said second angle element, said second clamping jaw being receivable on said second stud for clamping cooperation with said second angle element, a wingnut receivable on said second stud for urging said second clamping jaw into clamping relation with said second angle element.

50

element, and a readily removable pin hingedly connecting said first angle element and said second angle element to one another.

2. Apparatus as defined in claim 1 and additionally comprising a turnbuckle threadedly received on said second stud, a third stud threadedly received in said turnbuckle and secured to said second clamping jaw, a third clamping jaw, a fourth stud secured to said third clamping jaw and extending through said second clamping jaw, and a wingnut received on said fourth stud and urging said second clamping jaw into clamping relation with said third clamping jaw.

3. Apparatus as defined in claim 2, wherein one of said second and third studs is substantially longer than the dimensions of said first and fourth studs, jaws and elements.

15 4. Apparatus as defined in claim 2, and additionally comprising a pair of jammuts, one of said jammuts being received on said second stud in engagement with said second angle element, the other of said jammuts being received on said third stud in engagement with said second clamping jaw.

20 5. Apparatus as defined in claim 2 wherein said second angle element has an identical configuration to said third clamping jaw, each of said first angle element, second angle element and third jaw having a right-angle shape configuration, said first angle element including a yoke which straddles said second angle element.

25 6. Apparatus as defined in claim 3, wherein said one stud is said second stud.

7. Clamping apparatus comprising a first clamping element, a first clamping jaw mounted on said first clamping element and movable thereon in such a manner as to grip an object between said jaw and said element, a second clamping element, a readily removable pin hingedly mounting said second clamping element on said first clamping element, a second clamping jaw mounted on said second clamping element and movable thereon in such a manner as to grip an object between said second jaw and second element.

30 8. The clamping apparatus of claim 7, wherein said first element has a first passage therethrough and said second element includes a pair of projections which straddle the portion of said first element including said passage, said projections also having passages therein which are aligned with said first passage, said pin projecting into said passages and being readily removable therefrom.

35 9. Apparatus as defined in claim 1 additionally comprising a third clamping jaw having said second stud secured thereto, said second clamping jaw being received on said second stud, and a wingnut received on said second stud and urging said second clamping jaw into clamping cooperation with said third clamping jaw.
